UNITED STATES PATENT OFFICE.

ALBERT S. SAMUELS, OF SAN FRANCISCO, CALIFORNIA.

POCKET SALES-REGISTER.

1,323,495.

Specification of Letters Patent.

Patented Dec. 2, 1919.

Application filed August 8, 1917. Serial No. 185,154.

To all whom it may concern:

Be it known that I, ALBERT S. SAMUELS, a citizen of the United States, and a resident of the city and county of San Francisco and 5 State of California, have invented a new and useful Pocket Sales-Register, of which the following is a specification.

My invention relates to sales registers and one of the objects of my invention is to provide a sales register adapted to be carried in 10 the pocket of the salesman.

Another object of my invention is to provide a sales register which will prevent dishonest handling of money received from customers. 15

Another object of my invention is to provide a sales register comprising a sealed casing of inexpensive material, containing a supply of blank sales checks, and such that 20 when the last of the blanks is used, the seal or the casing must be mutilated in order to extract the strip on which the various sales have been recorded.

Another object of my invention is to provide a sales register comprising a non-refillable casing containing a quantity of blank sales checks, and so constructed as to retain therein a record of the filled-in checks, which cannot be recovered without 30 mutilating the casing.

The invention possesses other features of advantage, some of which, with the foregoing, will be set forth in the following description of the preferred form of my invention which is illustrated in the drawings accompanying and forming part of the specification. It is to be understood that I do not limit myself to the showing made by the said drawings and description, as I 35 may adopt variations of the preferred form within the scope of my invention as set forth in the claims.

Referring to the drawings:

Figure 1 is a vertical section taken lengthwise of the register.

Figs. 2 and 3 are views in vertical section of fragments of the upper and lower members respectively of the register casing. The views are arranged close together to 50 more clearly indicate the means for fixing the relative positions of the upper and lower members of the casing when assembled.

Fig. 4 is a plan view of a fragment of the

lower part of the casing, showing the construction of the corner.

55

Fig. 5 is a perspective view of the platen. The transfer sheet is shown attached thereto.

Fig. 6 is a side view of the magazine roll.

Fig. 7 is a side view of one of the feed 60 rollers.

Fig. 8 is a perspective view of the complete register.

Fig. 9 is a side view of a fragment of a register, showing a modified form of sealing 65 means.

Fig. 10 is a fragmentary view explanatory of Fig. 9.

The sales register of my invention comprises a casing preferably formed of two 70 mated members, which when secured together form a casing which cannot be opened without mutilation. A supply of blank sales checks in triplicate is assembled in the casing. Means are provided for permitting the recordation of sales data upon the uppermost blank and by transfer means forming a duplicate and triplicate copy thereof. Means are also provided for permitting the extraction from the casing of 80 the original and duplicate copies and for the retention therein of the triplicate copy. Preferably a seal is also applied across the line of union of the two parts of the casing so that opening it to tamper with or recover 85 the triplicate copy will involve a mutilation of the casing or of the seal or of both.

The register casing comprises two parts or members 2 and 3 adapted to be secured together to form a casing of such size and 90 proportion as to be easily slipped into an ordinary coat pocket. The closure or upper part 2 of the casing is provided with an aperture 4, and aligned therewith is a platen 6 upon which the blank checks 7 in triplicate from the magazine roll 8 rest while the user of the register is writing the record of his sales.

The platen 6, best shown in Fig. 5, is provided with sides 9 and an end 12 to form 100 a box-like member in which one end and face of the box have been omitted. The sides 9 and the end 12 form a support for the platen surface 6. The end 12 also forms a partition across the casing, as shown in Fig. 1, 105 thus forming a chamber C in which the

triplicate copies 7³ of the sales checks accumulate. The end 12 also acts as a stiffening member for the casing. The sides 9 of the platen structure also stiffen the side construction of the casing and form a backing or base upon which the sides are glued when the casing and closure are assembled. This reinforces the sides of the casing, keeps the joint tight, and helps to hold the two portions firmly together. The wall 12 joins the platen surface 6 in a smooth curve so that the strips 7 will run smoothly over the corner and for the same reason the platen at the opposite end is curved downwardly 15 into a lip 13.

The width of the platen structure is such that it fits snugly into the casing transversely. Its longitudinal position is fixed by corner blocks 14 and 16 at one end of 20 the casing and corner blocks 17 and 18 at the other end. The corner blocks also perform three other important functions. They form bearings for the magazine roll 8 and the feed rollers 19 and 21; provide 25 means for alining the two parts of the casing; and provide means for uniting the two parts of the casing on the inside beyond reach of interference.

As shown in Figs. 2 and 3, the block 14 30 is provided with a projection 22 and the block 16 is correspondingly recessed. Similarly formed blocks are arranged in each of the four corners of the casing and the interlocking of the blocks fixes the relative 35 positions of the members of the casing. It will also be clear that if glue or cement is applied upon the contacting surfaces 23 of the mated blocks, that a union is effected between the parts which is out of reach of any 40 non-mutilating opening force. Each of the blocks 14 is also provided with a recess 24 adapted to receive the journal 26 of the spindle 27 upon which the magazine roll 8 is held. When the magazine roll is dropped 45 into place, the journals 26 engaging in the recesses 24, and the upper part 2 of the casing is placed in position on the lower part 3, the blocks 16 close the recesses 24 and the magazine roll is securely but rotatably held 50 in position.

At the opposite end of the casing a similar arrangement secures the rollers 19 and 21. These rollers as well as the spindle 27 of the magazine roll, are preferably 55 entirely of wood turned to proper size and having suitable journals formed on the ends. The mounting of roller 21 is the same as that of the magazine roll. It is rotatable but otherwise is fixed in its bearings. The 60 roller 19, however, is held in a deep recess 29, and except as prevented by the roller 21 which overlaps it a small amount, is capable of limited vertical movement. The reason for this follows. The strips 7 of 65 sales checks in triplicate pass downwardly

from the platen lip 13, under the idler roller 19, up between the rollers 19 and 21, and around feed roller 21. At this point the strips separate, the two upper ones 7¹ and 7² passing out of the casing through a slot 31 and the triplicate copy 7³ passing around roller 21 and downwardly adjacent the curved end of the lower half of the casing, under roller 19 and back into chamber C. When the register is assembled the ends 75 of the upper two strips are left projecting from the slot 31 and the end of the triplicate strip turned downwardly against the curved end wall. The first blank check is then in position on the platen. To extract 80 the first check, the user grasps the protruding ends and pulls the strips out until the tear line between the checks is reached, when the first set is torn off, leaving short ends of the second set, so that the operation 85 may be repeated with each sale. Pulling the upper two strips 7¹ and 7² out causes the third and inner strips 7³ to be gripped against the feed roller 21. As the roller turns, the lower strip is fed downwardly 90 and rearwardly into the chamber C. The tension on the strips tends to lift idler roller 19, which therefore presses the pack or ribbon of three strips firmly against the feed roller 19. The tension placed upon the strips when pulling them out, is therefore 95 made to insure the proper alinement of the strips and the feeding of the triplicate backwardly into the chamber C.

A spring lip 32 is formed at the edge of 100 the aperture in the upper part 2 of the casing, adjacent the receiving end of the platen. This spring lip presses tightly against the strips on the platen and helps to keep them flat and smooth. Although the casing may 105 be made of any inexpensive material, it is preferably constructed of paper or comparable material and there is sufficient resiliency in this material to permit the suitably formed lip 32 to perform the function stated. 110

Preferably the intermediate strip of sales checks is quite thin, so that but one double-faced transfer sheet 33 need be used. This sheet is preferably stretched over the top of the platen 6 as shown in Fig. 5 and its ends 115 secured by paste to the sides 9. In assembling the register, the platen upon which the transfer sheet 33 has been mounted is set in position in the lower part 3 of the casing. The magazine roll 8 and the feed 120 roll 21 are then set in place and the strip 7³ inserted under the transfer sheet, the strip 7² lying against the upper surface thereof. The three strips together are then drawn out across the roller 21 and the roller 19 pushed down into position, carrying the three strips 125 downwardly and positioning them around the rollers as shown in Fig. 1. Next the end of the lower strips 7³ is tucked down between the roller 21 and the curved end of 130

the casing, and the closure 2 of the casing attached. Preferably a thin paper washer 35 is used on the ends of the magazine roll to protect it from glue or cement which may 5 exude from the surfaces 23.

After assembling the two parts of the casing, preferably a sealing strip 36, Fig. 8, is attached over the joint. An adhesive unaffected by ordinary agents is preferably 10 used and the sealing strip is preferably of a character impossible to duplicate easily or repair if mutilated, such as thin paper having printed on its face side an intricate design.

15 When the exhausted register casing is turned in to the office for the purpose of checking the triplicate sales checks against the duplicates turned in at the time of each sale, it requires but a brief inspection to 20 determine whether or not the casing has been tampered with in an effort to reach the triplicate strip. Obviously any effort to falsify the record of sales by withholding or altering the duplicates would be unavailing 25 unless the triplicate could also be altered to correspond.

An alternative method of sealing the casing is shown in Figs. 9 and 10. The adjacent edges of both part-casings at suitable points 30 are provided with tabs which are interlocked when the parts are assembled. Preferably four tabs 38 are disposed on the edge of part-casing 2, and four tabs 39 correspondingly disposed on the edge of part-casing 3. Two of each of the tabs 38 and 39 lie on the outside and two on the inside of the abutting edge as shown in Fig. 9. A wax wafer indicated by the dotted line 41, Fig. 9, is then melted over the interlocked 40 tabs and impressed with a suitable seal. One or more of such seals may be placed on each long side of the casing as desired. It is contemplated that the seal will be applied by the maker of the register and that 45 after the register has been broken open to extract the triplicate record of sales, it will be discarded. If the store using the register has a seal it will, of course, be possible to extract the triplicate strip, merely by breaking 50 the seal and to reload the register from time to time as needed, renewing the seal each time as a fresh magazine roll is inserted. In this case the surfaces 23 are not adhesively united, nor are the sides 9 attached 55 to the casing, the interlocking tabs and wax wafer holding the halves of the casing together. It is clear from the above that the sealing strip 36 may be of such a character that it serves not only to seal the joint between 60 the parts of the casing, but also to hold the parts together, other means being omitted.

Preferably each register is given an identifying number as indicated at 43, which 65 identifies the register with the salesman

using it. The sales checks also bear a number corresponding to that of the register in which they are assembled. Preferably the checks are numbered consecutively so that any missing one will be instantly detected. 70

I claim:

1. A sales register casing comprising a plurality of members, interlocking corner blocks arranged in said members for holding the members in alinement, and means on 75 the inside of said casing spaced from the joint between said casing members for attaching the interlocked blocks together.

2. A sales register casing comprising a plurality of members, interlocking blocks 80 arranged in said members for holding the members in alinement, and an adhesive interposed between contiguous surfaces of said blocks and spaced from the contacting edges of said alined members. 85

3. In a sales register, a casing, a closure for said casing, and means on the inside of said casing and closure for effecting a permanent union therebetween.

4. A sales register comprising a multi-part casing, means within the casing and out of reach of a non-mutilating force for permanently uniting said parts, a supply of sales checks arranged in the casing, means for permitting a recordation of data upon 95 said checks, and a seal arranged across the joint between said casing parts. 90

5. In a sales register, a two-part casing having an aperture therein, a platen underlying said aperture and having down-turned sides adhesively united to the adjoining walls of each part of said casing, whereby said walls are reinforced and kept in alinement. 100

6. A sales register comprising a two-part 105 casing having an aperture therein, a platen underlying said aperture, interlocking blocks for alining said parts and positioning said platen in said casing, a supply of sales checks in said casing, means for passing said checks across said platen, and a seal arranged across the joint between said casing parts. 110

7. A sales register comprising a two-part casing, corner blocks arranged in one of 115 said parts, a magazine roll of sales checks and a feed roll for said checks having journals disposed in recesses in said blocks, corner blocks arranged in the other part of said casing to close said recesses and form 120 bearings for said journals, means for permitting a recordation of data upon said sales checks, and means for uniting said casing parts to resist a non-mutilating opening force. 125

8. In a sales register, a casing, a platen arranged in the casing, a magazine roll of sales checks at one end of the platen, and feed rollers at the other end of the platen adapted to receive therebetween the sales 130

checks passing over said platen, one of said feed rollers being mounted to move transversely against the other to cause the sales checks to adhere thereto when the sales checks are placed under tension.

9. In a sales register, a two-part casing having an aperture therein, a platen arranged below the aperture, a magazine roll of sales checks at one end of said platen, feed rollers at the other end of the platen adapted to receive therebetween the sales checks passing over said platen, one of said feed rollers being movable toward the other to press said sales checks between said rollers when the sales checks are placed under tension, said casing being provided adjacent the feed rollers with an egress aperture for said checks, and means for uniting said casing parts to resist a non-mutilating opening force.

10. In a sales register, a two-part casing, corner blocks arranged in one of said parts, a magazine roll of sales checks and a feed roller for said checks having journals disposed in recesses in said blocks, corner blocks arranged in the other part of said casing to close said recesses and form bearings for said journals, and a second feed

roller having journals disposed in grooves in said blocks, said sales checks passing between said feed rollers, and said second roller being transversely movable in said groove bearings into operative engagement with said first-mentioned roller when said sales checks are placed in tension.

11. In a sales register, a two-part casing, blocks arranged in one of said parts, a supply of sales checks in said casing, a feed roller for said checks having journals disposed in recesses in said blocks, corner blocks arranged in the other part of said casing to close said recesses and form bearings for said journals and a second feed roller having journals disposed in grooves in said blocks whereby said roller is transversely movable into operative engagement with said first-mentioned feed roller, said checks being passed under said second roller, between the rollers and over the top of the first-mentioned roller.

In testimony whereof I have hereunto set my hand at San Francisco, California, this 19th day of July, 1917.

ALBERT S. SAMUELS.
